United States Patent Office.

SAMUEL S. SIMMONS, OF WATSONVILLE, CALIFORNIA.

Letters Patent No. 91,779, dated June 22, 1869.

IMPROVEMENT IN SEATS FOR VEHICLES.

The Schedule referred to in these Letters Patent and making part of the same.

To all it whom may concern :

Be it known that I, SAMUEL S. SIMMONS, of Watsonville, in the county of Santa Cruz, State of California, have invented an Improved Seat for Vehicles; and I do hereby declare the following description and accompanying drawings are sufficient to enable any person skilled in the art or science to which it most nearly appertains, to make and use my said invention or improvements without further invention or experiment.

My invention relates to an improved seat for vehicles, and more especially for sulkies and gigs, whereby the driver can always retain his seat.

The seat is mounted on an oscillating frame, and is held in an upright position by springs, placed on each side, at its lower end, which allows the seat to move from side to side, and permits the driver to maintain it in a vertical position at all times.

Springs are also arranged, so as to allow the seat to have a back-and-forward motion, thus rendering it much easier for the driver, than when the seat is fixed.

It also consists in providing movable, or adjustable stirrups for the feet of the driver, with which he can more readily accommodate himself to the movements of the sulky.

To more fully illustrate and explain my invention, reference is had to the accompanying drawings, and letters marked thereon, of which—

Figure 1 is a plan, with seat removed.

Figure 2 is a side sectional elevation.

Figure 3 is an end sectional elevation.

Similar letters of reference, in each of the figures, indicate like parts.

A and B are the thills, or shafts of a sulky, or other vehicle, having the two cross-pieces, C C'.

To the centre of these cross-pieces, upright standards D and D' are attached.

A square frame, E, having the two vertical posts, F F, descending from the centre of its opposite sides, is placed between the standards D and D', and turns, or oscillates on a bar, a, whose ends are attached to the standards.

The lower ends of the vertical posts are connected by a bar, b; and springs e e are placed on each side, their opposite ends resting against bars, or blocks G G'.

The seat H is mounted upon this frame, by means of metal bars, or rods e e, of sufficient strength to sustain the weight of the driver.

The ends of these rods are attached to the bottom of the seat, and are curved similar to a C-spring, and rest upon opposite sides of the square frame E.

Their opposite ends pass down, and are secured to a block, h,

At the point where the rods e e rest upon the frame E, they are secured by staples, which allow them to turn, but retain them in their proper positions.

The block h is shorter than the distance between the vertical posts F F, and springs i i are placed between its ends and the vertical post, which allows the seat to move backward and forward, when a weight is placed upon it.

Each rod may be continuous, if desired, having its ends secured to the bottom of the seat, and passing down and through the block h.

The rods e e, although they are bent in the form of a C-spring, need not be used for that purpose in sulkies and two-wheeled vehicles, as the thills are generally mounted upon springs; but in heavier vehicles, where springs are not used, they would be very convenient, and would not interfere with the other portions of the device.

A dog, K, is attached to one of the blocks, G, which may be forced down so as to clasp the short block h, and hold the seat stationary, when desired; and when it is not in use, it is raised up, and a link, k, thrown over its end, which retains it in that position.

The link can be removed from the end of the dog, by the foot of the driver, at any time, without stopping the horse, or moving from his seat.

In front of the cross-piece C, rods, or curved bars n extend forward, and are attached to the thills, as shown in fig. 1; and hanging stirrups o are attached, one end to the thills, and the other to the bars n.

These stirrups may be made of leather, or other yielding material, or they may be made of metal, and attached by screws, rivets, or bolts, so as to be adjustable.

By this construction of seats for vehicles, the danger of the driver's being thrown off, on account of the wheels coming in contact with some obstruction, is avoided, as the seat will yield in the proper direction, and thus accommodate itself to the driver.

The seat will be found more particularly valuable in sulkies and gigs, in turning corners, as the driver can, by throwing his weight to the proper side of the seat, always maintain a vertical position. Besides, it renders a seat more easy and comfortable in driving on level roads.

Having thus described my invention,

What I claim, and desire to secure by Letters Patent, is—

1. In combination with a seat for vehicles, the oscillating frame E, upright standards D D', springs e e and i i, together with the rods e e, the whole arranged substantially as described, for the purpose set forth.

2. In combination with the frame E, arranged as described, the device, consisting of the dog K and link k, for holding the same when required, substantially as described.

In witness whereof, I have hereunto set my hand and seal.

SAMUEL S. SIMMONS. [L. S.]
